PILE-FABRIC LOOM

Application filed March 22, 1929. Serial No. 349,207.

This invention relates to pile fabric looms for the production of cloth having either cut or uncut pile surfaces, and is more particularly directed to the pile wire controlling mechanism.

It is now the ordinary practice to provide looms of the above type with a pile wire carriage or horse and to actuate the carriage in one direction for the insertion of pile wires in the shed and in the reverse direction for withdrawing pile wires from the cloth. The requisite movements are now ordinarily imparted to the carriage or horse by a continuously driven chain for withdrawing successive pile wires from the cloth and a rope intermittently operated to insert the withdrawn pile wires in the shed.

During the withdrawal movement of a pile wire by the carriage the rope operating mechanism is usually idle and the rope is drawn outwardly by the outward movement of the carriage to which it is connected. The pull thus imparted to the rope or cable by the outward movement of the carriage or horse tends to stretch the rope and this tendency becomes emphasized when the loom is of extra width now demanded by the trade for the production of increased widths of rugs, carpets and the like.

Looms of this general type are usually provided with a switch having a guide-groove for the support of a pile wire as it is withdrawn from the cloth, and after the pile wire has been withdrawn and is held by the switch the latter is given a rearward movement to position the pile wire for insertion in the shed. During this movement of the switch the end of the pile wire then supported in the switch is liable to strike the heads or butts of the pile wires bound in the cloth as the switch is moved from its pile wire withdrawing to its pile wire inserting position.

An important feature of the present invention therefore consists of means for holding the pile wire carriage in its outer or retracted position against the contractile force of the rope, so that as the switch is moved from its pile wire withdrawing to its pile wire inserting position the end of the pile wire then in the switch will not contact with the heads

or butts of the pile wires bound in the cloth, and to effect release of the pile wire carriage by movement of the pile wire withdrawing chain.

Inasmuch as the withdrawn pile wire then in the switch is to be moved into pile wire inserting position, an appreciable time elapses between the release of the pile wire carriage from the chain and the positioning of the switch to its pile wire inserting position and the present invention therefore contemplates that after the pile wire carriage has been moved to its outer position and engaged by the carriage holding means, a further movement of the withdrawing chain is utilized to effect release of the carriage to its pile wire inserting movement.

The interval of time between the release of the carriage and the chain and the release of the carriage from the holding means will vary in different looms, and another feature of the present invention therefore consists in means for varying the interval between the release of the carriage from the chain and the release of the carriage from the holding means by the chain.

The invention and novel features thereof will best be made clear from the following description and the accompanying drawings of one good practical form thereof.

In the drawings:

Fig. 1 is a general front elevation of portions of a pile fabric loom containing the present invention;

Fig. 2 is a general plan view thereof showing the switch in its pile wire inserting position;

Fig. 3 is a front elevation on an enlarged scale with some of the parts broken away showing more particularly the features of the present invention; and

Fig. 4 is an enlarged sectional view on the line 4—4 of Fig. 2.

In the present drawings only a portion of the loom proper is shown, sufficient to illustrate the operation of the pile wire controlling means and, as usual, the loom frame consists of the side members 1, the lay 2, and shuttle box 3 and as these parts are of usual

construction their detailed illustration and description appears unnecessary.

Extending from one side of the loom is the supporting frame 4 on which is mounted the runway 5 which may be and preferably is of channel shape, as usual, the side members of which afford appropriate support for the pile wire carriage 6.

The pile wire withdrawing means consists of a continuously driven chain 7 having one or more lugs 8 and the upper run of the chain 7, as indicated in Fig. 2 at 9, travels in the troughlike guideway of the pile wire carriage support. The pile wire withdrawing chain passes about a guide-roll or sprocket 10 at the outer end of the supporting frame and about a similar guide or sprocket 11 at the inner end portion of the supporting frame, and the chain is driven continuously from the chain wheel 12 which as shown preferably consists of a sprocket wheel about which a portion of the chain 7 passes, and to guide the chain in its travel suitable guide-rolls or sprocket wheels 13 may be employed, it being understood that the chain wheel 12 is continuously driven from any suitable source of power now common and well understood in the art.

The pile wire inserting means consists of a rope or cable 14, one end of which is secured to the pile wire carriage 6 at 15, while the inner portion of the rope or cable passes about a guide pulley 16 at the inner end of the supporting frame 4.

As hereinbefore stated, the pile wire inserting rope or cable is intermittently driven to insert a pile wire in the shed, and then its driving means is disconnected from the source of power to permit the rope to be pulled outwardly by the carriage as it is moved to its outer pile wire withdrawn position. As indicated in the present instance of the invention, the pile wire inserting rope is actuated from the rope wheel 17 which is preferably formed with a scroll, as shown, to regulate the speed of pile wire insertion.

As the pile wire carriage 6 is moved outwardly by the chain the rope wheel is freed from its actuating mechanism and consequently the rope is pulled outwardly, under considerable strain in some cases, which has the effect of stretching the rope when the carriage has reached its outer position. When the carriage is in its outer position and is freed from its connection with the chain, as will presently appear, the contractile force of the rope tends to move the carriage inwardly.

As usual in pile fabric looms of the general type herein shown, the switch 18 is pivotally supported at 19 on a bracket 20 which may be conveniently secured to the supporting frame 4, the construction being such that the switch 18 may be moved frontwardly into its pile wire withdrawing position and after the pile

wire has been withdrawn it may be moved inwardly or towards the rear of the loom into pile wire inserting position, as indicated by full lines in Fig. 2.

When the switch 18 is being moved from its front to its rear position it contains a pile wire, as indicated in Fig. 2, and such movement of the switch to and from its two positions may be effected, as usual, by suitable means, herein typified by a link 21, Fig. 2.

During the movement of the switch from its pile wire withdrawing or front position to its pile wire inserting or rear position, the end of the pile wire, as at *a*, moves past the heads or butts *b* of the pile wires then bound in the cloth, and obviously if the contractile force of the rope or cable acts upon the carriage to move it inwardly to a slight extent upon its release from the chain, the end of the pile wire *a* is liable to engage the heads or butts of the pile wires then bound in the cloth, a condition that would mean breakage of parts.

In accordance with the present invention, therefore, means are provided for engaging and holding the carriage in its outer pile wire withdrawn position when it is released from the chain and effect release of the carriage from its holding means by continued movement of the pile wire withdrawing chain.

Pivottally mounted upon the pile wire carriage at 22, Fig. 3, is the dog 23 having a shouldered portion 24 adapted for engagement with one of the projections or lugs 8 on the pile wire withdrawing chain 7, to effect outward movement of the pile wire carriage.

Pivottally mounted at 25 on the pile wire carriage 6 is the locking lever 26, the lower end portion of which is adapted to engage a recess 27 in the dog 23 when the latter is engaged with a projection or lug 8 on the chain to thereby prevent any accidental release of the carriage from the pile wire withdrawing chain during withdrawal of the pile wire.

When the pile wire carriage has reached its outer position and the pile wire has been withdrawn and is held in the switch it is desirable that the connection between the chain and pile wire carriage be interrupted. It becomes desirable, therefore, that the locking lever 26 be first disengaged from the dog against the tension of its locking spring 28. Secured to the outer portion of the support 4 is a bracket 29 in which is mounted a locking lever trip 30, consisting of a roll, in the present instance of the invention, adapted to engage the upper end portion 31 of the locking lever and throw it out of action.

A positive disengagement between the dog and the lug or projection on the chain is effected by contact with the upwardly extending arm 32 of the dog which engages

5 a trip 33 secured to the bracket 29, the construction being such that the lock is first tripped to free the dog and then the dog itself is tripped into the position shown in full lines in Fig. 3, by engagement with the tripping device 33, whereupon, the carriage is entirely released from the pile wire withdrawing chain.

10 When the carriage is thus released from the chain, the contractile force of the rope or cable is liable to move the carriage inwardly and effect the undesirable results hereinbefore stated.

15 To prevent this inward movement of the carriage when released from the chain, the present invention provides a catch 34 pivotally mounted at 35 on a bracket 36 secured in fixed position on the support 4 or the upper troughway thereof, as indicated in Fig. 20. The catch 34 has a shoulder 37 adapted to engage a complementary shoulder 38 on the pile wire carriage 6 when the latter is in its outer position.

25 As hereinbefore stated, the catch 34 is pivoted at 35 and has a laterally extending tail portion 39 which is under the influence of a yielding plunger 40 mounted in fixed position on the supporting frame. The plunger 40 may preferably be under the influence 30 of a spring 41 in a housing 42 but obviously this feature may be variously contrived. To limit the swinging movement of the catch there is a stop 43 secured in fixed position on the support 4 and adapted to be engaged by 35 the end portion 39 of the catch when the latter is in its carriage holding position.

40 The construction described is such that as the pile wire carriage reaches its outer limit of pile wire withdrawing movement and is released from the pile wire withdrawing chain, the catch 34 comes into action to hold the carriage in its outer position, as indicated in Fig. 3.

45 An appreciable time, though small in extent, elapses between the disengagement of the pile wire carriage from the chain to permit the switch to be moved from its pile wire withdrawing to its pile wire inserting position and during this interval the catch 34 maintains the carriage in its outer position against the contractile force of the rope or cable.

50 The present invention utilizes the continued movement of the withdrawing chain 7 to trip the catch and free the carriage subsequent to the release of the carriage from the chain, and in accordance with the disclosed form of the invention in this respect the tail portion 39 of the catch has adjustably secured thereto 55 a lug or trip 44 which is engaged by the lug or projection 8 as the chain continues its movement towards the outer end of the supporting frame, the construction being such that after the carriage has been released from 60 the chain, as hereinbefore described, the con-

tinued outward movement of the chain causes the lug or projection 8 thereof to strike the inclined surface 45 of the lug or trip 44, lift the tail end portion of the catch in opposition to its spring 41, thereby freeing the carriage to its pile wire inserting movement after the switch has been moved into pile wire inserting position.

70 Inasmuch as the interval between the release of the carriage from the chain and the release of the carriage from the holding catch may vary in accordance with different conditions in loom construction, the present invention provides that the lug or trip 44 be adjustably secured to the tail 39 of the catch and 75 provides a series of depressions or teeth 46 adapted to engage projections 47 on the lug or trip 44 when the latter is moved lengthwise of the tail 39. To hold the lug or trip 44 in its determined position on the tail 39 suitable 80 means may be employed, such, for instance, as the screw bolt 48.

85 From the construction described as one good practical form of the present invention it will be apparent that when the carriage 90 has reached its outer position, as indicated in Fig. 3, and is released from the chain, the catch will hold the carriage for an interval of time until the projection or lug 8 on the chain contacts with the lug or trip 44 on the tail of the catch, with the result that any 95 inward movement of the carriage due to the contractile force of the rope will be overcome and the carriage held in its proper position to permit the switch and the wire held thereby to be swung to its wire inserting position before the carriage is released from the catch, and it will also be evident that the interval of time between the release of the carriage from the chain and its release from the 100 holding catch may be varied to suit conditions of use.

105 When the carriage reaches its outer pile wire withdrawn position it may sometimes be desirable to provide a yielding bumper or cushion against which the carriage may bear and upon which it may be held by the catch, and to this end as indicated in Fig. 2 there is a finger 49 pivotally mounted at 50 upon a bracket 51 extending laterally from the support 4 or the upper runway thereof. The face of the pivoted member 49 may conveniently be provided with a cushioning material 110 52 against which the carriage bears when it is in its outer pile wire withdrawn position.

115 53 What is claimed is:

1. In a pile fabric loom, the combination of 120 a pile wire carriage supported for movements to withdraw and insert pile wires, a pile wire supporting switch movable to one position for withdrawal of a pile wire from the cloth and to another position for insertion of a pile wire in the shed, mechanisms for moving the pile wire carriage to withdraw and insert pile wires, means for holding the pile 125 130

- wire carriage in its outer retracted position when released from the wire withdrawing mechanism, and means actuated by the withdrawing mechanism subsequent to the release 5 of the carriage therefrom to free the pile wire carriage to its pile wire inserting movement.
2. In a pile fabric loom, the combination of a pile wire carriage supported for movements to withdraw and insert pile wires, a pile wire 10 supporting switch movable to one position for withdrawal of a pile wire from the cloth and to another position for insertion of a pile wire in the shed, mechanism for moving the pile wire carriage to withdraw and insert pile 15 wires, a catch for holding the pile wire carriage in its outer retracted position when released from the withdrawing mechanism, and a part actuated by the pile wire withdrawing mechanism after it has released the 20 carriage to trip the catch and free the carriage to its pile wire inserting movement.
3. In a loom employing pile wires, in combination, a pile wire carriage supported for reciprocatory movement to insert and withdraw pile wires, a pile wire supporting switch 25 adapted to occupy one position during the insertion of a wire and a different position during the withdrawal of a wire, means for moving the carriage in the wire withdrawing 30 direction, a rope for moving the carriage in the wire inserting direction, means for holding the carriage in its withdrawn position against the tension of the rope, and a part controlled by the wire withdrawing means 35 for freeing the carriage from the holding means after the carriage has been released from the wire withdrawing means.
4. In a pile fabric loom, the combination of a pile wire carriage mounted for movements to insert and withdraw pile wires, a chain for imparting pile wire withdrawing movement to the carriage, a rope connected to the pile wire carriage for imparting pile 40 wire inserting movement thereto, a pile wire switch movable to and from position for inserting a pile wire in the shed, a catch for holding the pile wire carriage in its outer position against the contractile force 45 of the rope when the carriage is released from the chain, and means controlled by the continued movement of the chain for freeing the pile wire carriage from the catch after the carriage has been released from the 50 chain.
5. In a pile fabric loom, the combination of a pile wire carriage, a chain for moving the carriage to withdraw pile wires from the cloth, a rope or cable for moving the carriage 55 to insert pile wires in the shed, means for releasing the pile wire carriage from the chain when the carriage is in its outer position, a catch for holding the carriage in its outer 60 position from inward movement by the contractile force of the rope when the carriage has been released from the chain, and means

actuated by chain movement after release of the carriage from the chain to trip the catch and free the carriage to its wire inserting movement.

6. In a pile fabric loom, the combination of a pile wire carriage, a chain for moving the carriage to withdraw pile wires from the cloth, a rope or cable for moving the carriage to insert pile wires in the shed, means for releasing the pile wire carriage from the chain when the carriage is in its outer position, a catch for holding the carriage in its outer position from inward movement by the contractile force of the rope when the carriage has been released from the chain, 70 means actuated by chain movement after release of the carriage from the chain to trip the catch and free the carriage to its wire inserting movement, and means for varying the interval between the release of the carriage from the chain and its release from the catch.

7. In a loom employing pile wires, in combination, a pile wire carriage supported for reciprocatory movement to insert and withdraw pile wires, a rope or cable for moving the carriage in the wire inserting direction, a chain for moving the carriage in the wire withdrawing direction, latch means for holding the carriage in its retracted outer position, and latch releasing means operable by said chain and adjustable to different positions along the chain path to vary the time at which the carriage is released from the latch means.

8. In a pile fabric loom, the combination of a pile wire carriage, a chain for moving the carriage to withdraw pile wires from the cloth, a rope or cable for moving the carriage to insert pile wires in the shed, means for releasing the pile wire carriage from the chain when the carriage is in its outer position, a catch for holding the carriage in its outer position from inward movement by contractile force of the rope when the carriage has been released from the chain, and a lug carried by the chain to trip the catch after the carriage has been released from the chain.

9. In a loom employing pile wires, in combination, a pile wire carriage supported for reciprocatory movement to insert and withdraw pile wires, means for moving the carriage in the wire inserting direction, a chain for moving the carriage in the wire withdrawing direction, a latch for holding the carriage in the retracted position, and means carried by said chain and adapted to actuate the latch to release the carriage.

10. In a loom employing pile wires, in combination, a pile wire carriage supported for reciprocatory movement to insert and withdraw pile wires, means for moving the carriage in the wire inserting direction, a chain for moving the carriage in the wire withdrawing direction, a projecton on said chain 125

for pulling the carriage outwardly, a latch for holding the carriage in its retracted position, and means operable by said projection for actuating the latch to release the carriage.

5 In testimony whereof, I have signed my name to this specification.

EDWIN W. STONE.
